UNITED STATES PATENT OFFICE

JOHN NELSON, OF NEWTON, IOWA, ASSIGNOR TO AUTOMATIC WASHER COMPANY, OF NEWTON, IOWA, A CORPORATION OF DELAWARE

WRINGER HEAD FOR WASHING MACHINES

Application filed June 1, 1928. Serial No. 112,830.

This invention relates to wringer heads for washing machines, the same being fashioned in a manner to contain the driving and reversing gearing mechanism for the well known wringer.

One of the objects of the invention is in the provision of a wringer head, fashioned in a simple manner, to provide a compact arrangement of driving and reversing gear mechanism, as well as permitting ready access to the gearing in case of breakage or any necessary replacement of parts.

Another object is in the provision of a wringer head of simple design, the same being adapted to compactly house the gear mechanism therein, and to permit ready assembly and demountability of the parts contained therein and therefore making possible a quick replacement of broken or worn parts.

Still another object resides in the fashioning of a wringer head, wherein the head portion provides the bearing surfaces for the entire meshing gear portions therein, there being such an arrangement of parts as to permit ready assembly and demountability.

A further object is in the provision of a wringer head of simple design, wherein the driving, reversing and pinion gears and clutch member are arranged in such manner that the various portions may be readily assembled and readily replaced in case of breakage or wear, without removal of the head or in any manner displacing any other portions of the wringer.

A still further object is in the provision of a wringer head having the gear and clutch mechanism contained therein, fashioned in a manner with respect to the head, to permit ready assembly and demountability.

Other objects will appear in the following specification, taken in connection with the annexed drawings, in which—

Fig. 1 is a front elevation of the wringer head, with the cover removed; and

Fig. 2 is a cross-sectional view showing in detail the manner of mounting the gear and clutch mechanism.

Referring to the drawings, there is shown the wringer head and contained gear and clutch mechanism, although it is apparently

obvious that my device is adapted for use in connection with any type of wringer mechanism, the same being used upon the power operated washing machines. It is thought that the art as respects power operated washing machines is so well known, as not to make necessary the showing of a wringer mechanism in connection with the wringer head and the mounting of the same upon a power operated washing machine. This application is directed entirely to the wringer head and it is obvious that it is adapted for use in connection with any of the well known types of wringer, as well as any type of power operated washing machine wherein a wringer mechanism is to be driven simultaneously therewith.

The wringer head herein includes the following elements: A housing, generally referred to as 10, has the cylindrical portion 11, which slides over a similarly shaped receiving portion upon a power operated washing machine, not shown. An abutment plate 12 maintains the wringer head in proper relationship with that portion of the washing machine to which the wringer head is attached. A power operated shaft, not shown, is adapted to mate with the stub shaft 13, which transmits power to the various gears later to be described, and finally to the wringer, also not shown. The housing 10 has the brackets 14 integrally formed thereon, adapted to receive any of the well known types of wringer, the main portions of which include the rubber roll members. An aperture 15 in the housing 10 permits entry of the drive shaft, not shown, of the wringer, not shown, and mating thereof with the horizontally disposed short shaft 16.

Before describing in detail the various gear mechanisms contained in the wringer head, it might be stated that this head to which the wringer is attached, is adapted to swing about the portion of the washing machine upon which it is slidably mounted, as before explained.

To locate the wringer head at various desired points in its swinging movement, there is provided a lug member 17, which is adapted to be moved manually upwardly against the

tension of the spring 18. This lug, in its raised position, permits manual movement of the wringer head and wringer about its pivot, and upon release of the lug 17, the same is adapted to engage apertures, not shown, in adjacent portions of the washer, and therefore to hold the wringer in the desired position. The interior of the housing 10 is fashioned to provide a support or bearing 19 for 10 a bevel gear 20. The hub 21 of the bevel gear 20 rotates in this before mentioned bearing 19, the same being normally loosely mounted, as respects its hub 22, with the before mentioned horizontal shaft 16. A pinion gear 15 23 is pinned, as at 24, to the stub drive shaft 13, the housing portion 10 also providing a bearing surface 25 for the stub shaft 13. Keyed as at 26 to the horizontal shaft 16 is the clutch member 27. Means for entirely 20 enclosing the housing 10 is provided in a cover 28 attached to the housing by means of screws 29 passing therethrough, and threaded into the spaced receiving portions 30. The cover 28 has integrally formed upon its inner 25 face a bearing 31 for a second bevel gear 32. This latter gear is loosely mounted upon the horizontal shaft 16, as is the before mentioned bevel gear 20. The horizontal shaft 16, as before described, is adapted to mate 30 with an extended portion of the drive shaft for the wringer, not shown, and the above described gear and clutch mechanism is provided for the purpose of controlling the direction of movement of the wringer roll. Means 35 for controlling the movement of the clutch 27 is provided in the following mechanism: The manually operable handle 33 has keyed thereto as at 34, a vertically disposed shaft 35, 40 slideable in the upper portion of the housing 10, the lower end thereof 36 having a cam surface and being adapted, upon movement of the handle 33, to clutch either of the adjacent gears 20 or 32, to the horizontal shaft 16. A lug 37 is keyed, as at 38, to the vertical shaft 35, thus preventing vertical withdrawal of the cam 36 from engagement with the clutch 27 and frictionally holding the handle 33 upon the upper end of the housing 10. A means for increasing the friction of 45 the handle 33 with the upper portion of the housing 10 is provided in a spring tension ball 39, adapted to engage recesses 40 disposed at points in the travel of the handle, which will insure the holding of the clutch 50 either in a neutral position, or in engagement with either of the gears 20 or 32, as desired.

As respects the operation of the wringer head and contained gear and clutch mechanism, such operation is substantially the 55 same as practically all wringer heads, in that movement of the clutch which is transmitted thereto by manual movement of the handle 60 33, effects either a clutching of the gear 20 to the horizontal shaft 16 or the gear 32 to said shaft. Similarly, a movement of the

handle to a neutral position prevents any rotation of the horizontal shaft 16. Obviously, this clutch mechanism controls the direct rotation of the rolls of the wringer, not shown, the reversing thereof and the prevention of any movement at all when the clutch is in a neutral position. 70

As stated in the objects of the invention, applicant has devised such a gear head as will permit the use of a very few parts, these parts being arranged in a manner to insure ready assembly and demountability thereof when desired. The assembly feature of the present wringer head is perhaps not as important as the demountability feature, in that once the wringer head is attached to the washing machine and the wringer attached to the head, there is, under ordinary circumstances, the necessity of almost a complete disassembly of the gear head to replace any worn or broken parts. In the present instance, the housing and cover therefor provides a bearing support for the bevel gears 20 and 32, as well as a bearing support for the pinion gear and controlling means for the clutch. 80

It is apparent from the drawings that the various elements might be readily assembled in the complete wringer head shown in the drawings, but as respects the ready demountability thereof, which is necessary when a portion thereof is either broken or worn out, we find that all that is necessary to replace said part is to unscrew the cover 28, whereupon the gear 32 may be removed from the horizontal shaft 16 and as a matter of fact, the horizontal shaft 16 withdrawn from the gear 20, as well as from its mated engagement with the wringer shaft, not shown. The removal of the horizontal shaft 16 permits now the manual taking out of the clutch 27. 90

Should it be necessary to further disassemble the wringer to replace some other part, the pin 24 may be withdrawn and therefore the stub shaft 13 and pinion gear removed. If a still further demounting of the wringer is necessary, by unscrewing the member 34, the vertical shaft 35 with the connected lug and cam portion thereof may be removed, whereupon the inner gear 20 may likewise be withdrawn from its bearing 19 which is a part of the housing. 100

It is obvious from the above that all of the now disassembled gears, clutches, shafts, etc. may be readily assembled and any portion thereof that has been broken or worn may be replaced. 110

Applicant bases his present application entirely upon his above described wringer head, and the particular formation and arrangement thereof, which permits the above described ready assembly and removal of elements thereof. 120

What I claim is:

A wringer head for wringer rolls comprising a housing having the side opposite the

wringer rolls removable, oppositely disposed bevel gears freely mounted in bearings in said housing and removable side, a horizontal shaft freely mounted in said gears and slideable therein, said shaft being adapted to 5 clutch with the drive shaft of the wringer rolls, a clutch member slidably splined on said shaft, whereby said horizontal shaft and clutch member may be disengaged from said 10 gears by the withdrawal of the horizontal shaft from the gears, a drive shaft pivotally mounted in the housing proper, a pinion pinned on said drive shaft and engaging said bevel gears, a clutch controlling shaft pivotally 15 mounted in said housing, a manually operable handle, and releasable connecting means between the clutch controlling shaft and handle.

In testimony whereof I have hereunto affixed my signature.

JOHN NELSON.
